UNITED STATES PATENT OFFICE.

OTTO ZACHOW, OF CLINTONVILLE, WISCONSIN.

DEVICE FOR GRINDING WATER METERS.

Application filed February 28, 1922. Serial No. 540,069.

To all whom it may concern:

Be it known that I, OTTO ZACHOW, a citizen of the United States, residing at Clintonville, in the county of Waupaca and State 5 of Wisconsin, have invented new and useful Improvements in Devices for Grinding Water Meters, of which the following is a specification.

This invention relates to grinding devices,
10 and especially for grinding the oscillatory
disc pistons of water meters.

The object is to provide a device of this character which may be readily applied to the upper portion of the measuring chamber of an ordinary water meter, in which the disc form of piston is employed, the device having means for engagement with the drill chuck of an ordinary drill press which may be employed for imparting rotary motion to an attachment which, in turn, causes the disc piston to rotate and to rock in the same manner as when driven by the pressure of the water in its normal operation as a meter, the said measuring chamber and piston being adapted to be immersed in a pan or other receptacle containing a grinding fluid while being supported on the bed plate of the drill press, suitable clamps, braces or holding means being employed for holding the non-revolving shell or bearing portion of the grinder from turning while the operation is in progress.

35 A full and complete understanding of the invention may be obtained from a consideration of the following detailed description, taken in connection with the accompanying drawing forming a part of this specification, it being understood that while the drawing shows a practical form of the invention, the 40 latter is not confined to strict conformity therewith, but may be changed or modified so long as such changes or modifications mark no material departure from the salient features of the invention as specifically 45 pointed out in the appended claims.

In the drawing, in which similar reference characters designate corresponding parts throughout the several figures,

Figure 1 is a vertical sectional view of the improved grinder applied to the piston chamber of an ordinary disc piston water meter;

Figure 2 is an inverted plan view of the grinding device, a simple form of holding clamp being shown in connection therewith;

Figure 3 is an elevation of an interiorly threaded sleeve used in the device;

Figure 4 is a similar view of the driving spindle thereof; 60

Figure 5 is a horizontal section on the line 5-5 of Figure 1;

Figure 6 is a similar section on the line 6-6 of Figure 1.

In water meters most generally used, an outer casing comprising upper and lower sections is employed in which are housed, in the said lower section, an interior casing confining a rotary and oscillating disc piston, which has suitable connection with registering mechanism housed in the upper section of the outer casing, and so arranged, by means of gearing, as to indicate at any time the quantity of water which has passed through the meter. The lower section of the outer casing has suitable nipples for connection to a pipe line in order to allow the water to enter at one side and to pass out at the other, and the interior casing located in the lower section is also provided with inlet and outlet passages so that the disc piston may be actuated thereby, the said piston being prevented from revolving about its own axis by suitable, vertically disposed walls, but free to rock about a central point in a well known manner, and to cause an upwardly directed pin to impart rotary motion to a vertical shaft included in a train of gears.

In the continued use of the meter the interior casing, having the disc piston located therein, is subjected to the passage of great quantities of water and frequently becomes clogged with accumulations of sediment, which first impedes the operation of the piston and gearing to an extent that accurate registering of the quantity of water passed is impossible, and then becomes so covered and filled with the accumulations, that the meter becomes useless unless the parts are moved and cleaned or repaired or replaced with new members.

The above briefly described parts of an ordinary water meter form no part of the present invention, which is concerned with means for grinding and renewing the piston, by removing all accumulations in the piston casing. 105

It has not been deemed necessary, in the drawing, to illustrate the construction of the water meter in detail, nor the operation of the same, only the piston and casing for 110

the same being shown. The casing, constituting a measuring chamber, comprises a lower section 1 and an upper section 2, suitably fitted and held together, and so shaped 5 as to permit of the rocking movement of a disc 3 which constitutes a piston. This casing is usually formed of brass or some other non-corrodible metal, while the disc is made from hard rubber or some similar material, 10 which is not subject to the action of the water and which is strong and light in weight.

The disc 3 is carried by a centrally located ball 4 having bearings in the upper 15 and lower walls of the casing, and is provided with a radially disposed slot 5 straddling a vertical wall 6 within the casing, and thus held from axial rotation while allowed to rock, the said ball having an axially disposed pin 7 extending upwardly through the upper ball bearing. The casing is provided with a water inlet on one side and a water outlet on the other side, neither of which are shown, while the upper portion of the piston 20 casing is provided with an upstanding annular flange 8 provided with threads in its inner wall.

The invention comprises a tubular sleeve or casing 9, having one end reduced to provide 30 an extension 10 which is exteriorly threaded and of a diameter to be screwed into the said flange 8 of the piston casing, the shoulder thus formed resting upon the upper edge of the flange. The casing 9, at the threaded end, is provided with a counterbore 11 extending one-third the length of the same, and a bore 12 of reduced width which extends the remaining portion of the casing. A shoulder 13 is provided at the junction 35 of the two bores. Extending from this shoulder to a point near the other or upper end of the sleeve is a longitudinally disposed groove 14, constituting an oil groove, and at the upper end of the same the casing is provided with a transverse bore 15 which is 40 suitably threaded for the reception of a screw 16 for a purpose to be explained.

Adapted to the bore 12 through the casing 9 is an inner sleeve 17, of a diameter to freely slide therein, said sleeve having at its lower end an outstanding flange 18, adapted to abut against the interior shoulder 13 of the casing and to form a thrust bearing for the inner sleeve and prevent its upward movement. In line with the screw 50 16, the inner sleeve 17 is provided with a peripheral groove 19 which is adapted to receive the inner end of the said screw at any point, and to prevent any downward movement of the sleeve within the casing when the device is being applied for operation.

The sleeve 17 is internally threaded for 55 the reception of a correspondingly threaded spindle 20 having at its lower end a head

21, circular in form and adapted to snugly fit the counterbore 11 of the casing 9, and provided at one side with an undercut inclined slot 22, into which is adapted to loosely fit the upstanding pin 7 of the piston disc 3. At the upper end the spindle 20 is provided with a reduced portion 23 having one side flattened and adapted to enter the chuck 24 of an ordinary drill press, or any other suitable part of a machine having means for turning the device, the said chuck having the usual set screw 25 for maintaining the connection. The threaded portion of the spindle 20 extends somewhat above the upper end of the casing 9 and receives a clamping nut 26 applied thereto, with a washer 27 interposed between the same and the upper end of the casing, said washer being of a diameter to extend over and bear upon the said upper end and to form a thrust bearing in opposition to the aforesaid flange 18.

In operation, the piston casing 1 is removed from the water meter and placed within a pan, indicated in dotted lines at 28 in Figure 1 of the drawing, while said pan is supported on the bed plate of the drill press directly beneath the chuck 24. Any suitable means, such as clamping member 29 which may be formed of wood and held in clamping relation by a bolt 30 may be employed to hold the casing from turning, and the pan is filled with any suitable grinding fluid, such as emery and oil, to a level above the casing members 1 and 2, so that the interior of the casing may be flooded with the same and subjected to the grinding action thereof, when the rotation of the drill press is started after the parts are properly connected.

In applying the grinder to the piston casing, the screw 16 is tightened against the inner sleeve 17 to prevent the latter from turning in the casing 9, when, by unscrewing the nut 26 sufficiently, the spindle 20 may be screwed through the sleeve 17 to bring the head 21 near to or projecting below the lower end of the extension 10 of the casing. The inclined pin 7 of the piston may then be introduced into the undercut slot 22 of said head, and the extension threaded into the upstanding flange 8 of the piston casing. After the casing 9 is seated, the spindle 20 may be screwed upwardly through the inner sleeve 17, which is held from rotation within the casing 9 by means of the screw 16, until all binding action of the pin 7 within the slot 22 is relieved, when the clamp nut 26 is tightened down against the washer 27, which binds the spindle 20 within the inner sleeve 17 and the screw 16 is then released, when the movable parts are free to rotate within the casing 9 to proceed with the grinding operation.

When it is desired to lubricate the interior of the body member in order that the sleeve 17 and head 21 may freely revolve, the screw 16 may be removed from its seat and the lubricant introduced through opening 15, the groove 14 facilitating the feed of the same.

From the foregoing it will be seen that a simple and cheaply manufactured grinding device has been provided, which may be readily applied to the piston casing of water meters of the disc piston type, and operated to grind the same while under the action of proper grinding fluids to remove all accumulations therefrom and permit of further continued and effective use of the meter.

What is claimed is:—

1. A grinding attachment for water meters comprising a body member, means at one end of said member for detachable connection with the piston casing of the meter, an inner sleeve slidably fitted in the body member, means for holding said sleeve from longitudinal movement, a spindle traversing the said sleeve and adjustable longitudinally therein, means for causing the spindle and sleeve to revolve together, and means formed on the lower end of the spindle to oscillate the meter piston when said spindle rotates.

2. A grinding attachment for water meters comprising a body member, means at one end of said member for detachable connection with the piston casing of the meter, an inner sleeve slidably fitted in the body member, means for holding said sleeve from longitudinal movement, a spindle traversing the said sleeve and adjustable therein, means for causing the spindle and sleeve to revolve together, and a head formed on the lower end of the spindle and provided with a slot to receive the upstanding inclined pin of the meter piston, said spindle being projected from the body member and having means for connection to a source of power.

3. A grinding attachment for water meters comprising a body member having a threaded extension at one end for connection with the piston casing of the meter, a spindle operatively mounted within the body member for rotary and longitudinal movements, said spindle provided with a head at its inner end formed with a slot to receive the upstanding pin of the meter piston, and said spindle being extended beyond the body member and provided with means for connection to a source of power for rotating the same.

4. A grinding attachment for water meters comprising a body member threaded at one end for connection with the piston casing of the meter, said body member having a main bore and a counterbore at one end of the main bore, an inner internally thread-

ed sleeve slidably fitted within the bore of the body member, means for holding the said sleeve from longitudinal movement, a threaded spindle traversing and engaging the threads of the said sleeve and adjustable 70 therein, and a head formed on one end of the spindle to fit the counterbore of the body member, said head being provided with a slot to receive the upstanding pin of the meter piston to impart rotary motion thereto 75 when the spindle is revolved, said spindle being projected beyond the body member and provided with means for connection with a rotatable mechanism.

5. A grinding attachment for water meters, comprising a body member having a threaded extension at one end for connection with the piston casing of the meter, means engaging with the body member for holding the same from movement, an internally threaded sleeve slidably fitted within the body member and provided with means for holding said sleeve from longitudinal movement, a threaded spindle traversing said sleeve and adjustable therein to have 90 both rotary and longitudinal movements, and means at the inner end of the spindle for detachable connection with the piston casing of the meter, said spindle projecting from the body member and having means for connection with a source of power to rotate the same.

6. A grinding attachment for water meters comprising a tubular body member having a threaded extension at one end for connection to the flange of the disc piston casing of the meter, said body member having its bore reduced at the end opposite the threaded extension to provide a shoulder, an inner, internally threaded sleeve slidably fitted in the body member and having a flange at one end abutting the said shoulder and provided with a circumferential groove near its opposite end, a screw set through the wall of the body and entering the said groove to hold the inner sleeve from longitudinal movement, a threaded spindle traversing the inner sleeve and adjustable therein, a head formed on the lower end of the spindle of a diameter to fit the larger, lower end of the bore in the body, and provided with an under cut slot to receive the upstanding, inclined pin of the meter piston to impart rotary motion thereto when the spindle is revolved, a binding nut and an interposed washer mounted on the spindle to bind on the upper end of the body, in opposition to the internal flange and shoulder, said spindle having means for connection 105 with a drill chuck.

In testimony, that I claim the foregoing as my own, I have hereto affixed my signature.

OTTO ZACHOW.
